Patented June 5, 1928.

UNITED STATES PATENT OFFICE.

EDUARD ROTHMANN, OF DRESDEN, GERMANY.

STEEL-ENGRAVING-PRINTING MACHINE.

Application filed November 1, 1928, Serial No. 145,601, and in Germany November 17, 1925.

This invention relates to a steel engraving printing machine for the mechanical printing of steel engraved printed products, for instance congratulation cards, visiting cards, heads of letter paper and the like. The printing machines of this type which have become known are rather expensive owing to their complicated construction and to their heavy weight.

The steel engraving printing machine according to the invention is distinguished by light weight and considerable output so that it is a steel engraving printing machine specially adapted for small and medium printing offices. The most essential characteristic feature of the new steel engraving printing machine is the extraordinarily simple driving mechanism for the movements of the element which exerts the printing pressure and also for the inking and wiping mechanism. In order to obtain a high printing pressure, a double-armed platen with especially long lever arms is provided in the improved steel engraving printing machine in opposition to machines of known type, the platen being controlled by a link system of the simplest kind.

An embodiment of the invention is shown, by way of example, in the accompanying drawing in which:-

Fig. 1 shows the improved printing press in side elevation in the position of printing.

Fig. 2 is a similar view, the elements being in the laying on position.

In the drawings a' is the frame of the machine with the driving shaft a^2 which carries the crank disc a^3 .

The platen lever b oscillatable around the pivot point a is controlled by a lever d which is oscillatably mounted on a pivot pin c . The amplitude of the oscillation of the lever d is produced by means of a crank rod g which is hingedly connected to the lever d at f and by the crank h of the crank disk a^3 .

In the platen lever b a longitudinal slot e is arranged which is of such shape that it ensures as great an amplitude of oscillation of the platen as possible. In the printing position of the platen, shown in Fig. 1, the pressing moment becomes effective in the extreme point of the slot e . The printing block i is brought from the printing position shown in Fig. 1 into the inking position shown in Fig. 2 by means of a lever l oscillatably mounted on a pivot pin k . The holder m for the block i is fixed on a rod

system n which at its lower end is connected to the lever l by means of a link o . The levers l and d are hingedly connected to the crank rod g by the common pivot bolt f . For this reason a guide slot p is arranged in the lever l . The elements q , r , s , t , u form part of the inking mechanism known per se. The wiping mechanism for the ink adhering to the surface of the block is designated by v , w , x , x' , y , z .

The driving mechanism as above described may be used evidently also for book printing machines, offset printing machines, intaglio printing machines, or other printing machines. These applications of the driving mechanism form part of the invention.

I claim:-

1. A steel engraving printing machine comprising in combination, a two armed platen, a comparatively long lever arm of said platen said lever arm having a longitudinal guide slot, an inking and wiping mechanism, and a lever system for controlling said platen and said inking mechanisms.

2. A steel engraving printing machine comprising in combination with the machine frame, a driving shaft journaled in said frame, a crank disk on said driving shaft, a crank on said disk, a crank rod, a pivot pin at the outer end of said crank rod, a two armed platen having a comparatively long lever arm, a driving lever for said platen, an inking and wiping mechanism, a lever system for operating said inking mechanism from said crank disk, a block holder, rods carrying said block holder, and a pivoted lever for operating said block rods, said last mentioned lever and said driving lever for the platen being operated from said pivot pin at the end of said crank rod.

3. A steel engraving printing machine comprising in combination with the frame, a driving shaft journaled in said frame, a crank disk on said driving shaft, a crank on said disk, a crank rod, a pivot pin at the outer end of said crank rod, a two armed platen having a comparatively long lever arm with a longitudinal curved slot, a driving lever for said platen pivotally fixed at the lower end to the machine frame, a pin at the top end of said lever engaging with said slot of the platen lever, an inking and wiping mechanism, a lever mechanism for operating said inking mechanism from said crank disk, a block holder, rods carrying said block holder, and a pivoted lever for operating

said block rods, said last mentioned lever and said driving lever for the platen being operated from said pivot pin at the end of said crank rod.

5 4. A steel engraving printing machine comprising in combination with the frame, a driving shaft journaled in said frame, a crank disk on said driving shaft, a crank on said disk, a crank rod, a pivot pin at the outer end of said crank rod, a two armed platen having a comparatively long lever arm with a longitudinal curved slot, a driving lever for said platen pivotally fixed at the lower end to the machine frame, a pin at the top end of said driving lever engaging with said

slot of the platen lever, an inking and wiping mechanism, a lever mechanism for operating said inking mechanism from said crank disk, a block holder, rods carrying said block holder, a link at the lower end of said rods, a lever pivotally fixed to the machine frame and hingedly connected to said link and having a longitudinal slot, said last mentioned lever and said driving lever for the platen being operated from said pivot pin at 20 the end of said crank rod said pivot pin engaging with the said longitudinal slot of the 25 pivotally fixed lever for the block holder.

In testimony whereof I affix my signature.
EDUARD ROTHMANN.
